UNITED STATES PATENT OFFICE

CORNELIUS B. WATSON, OF CHICAGO, ILLINOIS, ASSIGNOR TO GYRO PROCESS COMPANY, OF DETROIT, MICHIGAN, A CORPORATION OF MICHIGAN

METHOD OF TREATING PETROLEUM OILS

Application filed August 21, 1928. Serial No. 300,997.

This invention relates to an improved method of treating hydrocarbon oils such as crude oils or other oils containing fractions of widely differing boiling range, and has for its primary object the provision of an efficient system of heat treating such oils for the purpose of obtaining fractional separation thereof, and in certain instances the vapor phase conversion of one or more of the higher boiling fractions so separated into fractions or compounds of lower boiling range.

It is another object of the invention to provide an oil treating system wherein the oils charged thereto may be in the form of crude oil containing appreciable quantities of free or natural gasoline and wherein an improved method of heat interchange is provided for the purpose of separately removing from the system the free gasoline or other natural low boiling point compounds from the charging stock prior to the circulation of the main body of oil through the principal heating and converting zone of the system. It has been observed that free or natural gasoline obtained from paraffin base hydrocarbon oils is often not as desirable as a fuel for internal combustion engines as the so-called cracked or synthetic fuels, especially such fuels as are produced by high temperature or vapor phase cracking. This is due to the fact that natural gasoline of the character specified has a decided tendency to knock or detonate when exploded in the cylinders of an engine, whereas the cracked fuel is substantially non-detonating. Heretofore in charging crudes to cracking equipment, it has been the custom to allow the vapors of natural gasoline to intermingle with the vapors produced by the cracking operations, with the result that a blended fuel, containing both the natural gasoline and the cracked gasolines is produced and the blending results in a fuel of lower anti-knock value. Therefore, the present invention provides a system for charging crude to a vapor phase cracking still and the securing a sufficient heat interchange and in accomplishing this operation in such a manner that the vaporized natural gasoline is separately discharged from the system with respect to the vaporized cracked gasolines.

It is another object of the invention to provide a heat exchanging system which receives its heating medium from the oil vapors discharged from the converting unit of the system, and to situate within said heat exchanger a coil or the equivalent thereof through which the fresh charging stock is circulated, in order that the heat contained in the vapors discharged from the converter may be transferred through said coil and absorbed by the charging stock circulating therethrough, whereby the temperature of the latter may be elevated sufficiently to distill off the free gasoline content therein present.

It is another object of the invention to use the higher boiling compounds of the charging stock, after the removal of the low boiling compounds, for the purpose of cooling the vapors released from the converting unit of the system by bringing such high boiling materials into direct contact with the converter vapors in order that the temperature of such vapors may be sharply and instantaneously reduced to prevent further cracking reactions taking place therein.

For a further understanding of the invention, reference is to be had to the following description and the accompanying drawing, wherein the figure represents diagrammatically apparatus which may be employed in carrying out the features of the invention.

In the accompanying drawings the numeral 1 designates a converter or other type of heating apparatus through which oil is circulated and heated to a temperature sufficient to effect conversion and to reduce the oil to a dry vaporous state. Leading from the outlet side of the converter 1 is a pipe line 2 which extends into the casing of a heat exchanger 3.

Arranged within this heat exchanger is a closed coil 4, the inlet side of which is connected with a pipe line 5 which leads from a supply tank 6 or other storage point for the charging stock and which is preferably crude oil containing normal quantities of free gasoline. The pipe line 5 is preferably provided with a pump 7 to effect the forced passage of the oil from the tank 6 through the line 5 and thence through the coil 4 situ-

ated within the casing of the heat exchanger 3.

The outlet line 8 of the coil 4 leads to a closed separator 9 wherein there takes place a separation of the free gasoline from the heavier fractions of the charging stock pumped through the coil 4, it being understood that the oil while passing through the heat exchanger and within the coil 4 is heated sufficiently by indirect contact with the heated oil vapors, released from the converter, to permit of the vaporization of the gasoline fraction of the original charging stock. This gasoline fraction passes overhead by way of the line 10 to a condenser 11 and is then transferred to a free gasoline storage tank 12.

The unvaporized oil which collects in the bottom of the separator has boiling points materially higher than those of the free gasoline or other low boiling point materials. This relatively heavy oil in liquid form is then forced by way of a pipe line 13 and a pump 14 through a nozzle 15 situated within the casing of the heat exchanger 3. The nozzle 15 is so disposed within the heat exchanger that the oil released therefrom is brought into intimate contact with the highly heated cracked oil vapors discharged from the converter 1. For example, the vapors discharged from the converter 1 flow through the line 2 and into the heat exchanger 3 at a temperature of approximately 1100 degrees F. This temperature is substantially instantaneously lowered by contact with the relatively colder oil discharged from the nozzle 15. The temperature of the oil forced through the line 13 at or near the nozzle may be approximately 300 degrees F., and due to this relatively low temperature it will be seen that the temperature of the oil vapors of the converter will be practically immediately lowered to a temperature not in excess of 600 degrees F., thus preventing further cracking reactions taking place in the converted vapors. These temperatures are sufficient to heat the coil 4 to secure the "topping" of the charging stock forced through said coil.

The vapors remaining in the heat exchanger pass overhead by way of a line 16 to suitable fractionating and purifying apparatus 16a which permit a final motor fuel product to be obtained. The liquid unvaporized oil in the bottom of the heat exchanger is discharged by way of a pipe line 17 and is circulated or recirculated through the converter 1.

In view of the foregoing it will be seen that the present invention provides a simple yet effective method of heat interchange which is both effective in operation as well as economical. The system permits the crude charging stock to be readily deprived of its free gasoline content and to permit the re-

maining fractions to be employed as a charging stock for an oil conversion system with marked heat economy. Another feature of the invention resides in the fact that by reason of sharp cooling of the oil vapors released from the converter and the practically instantaneous arresting of the conversion reactions, little or no deposit of free carbon in the system takes place.

The liquid condensate which accumulates in the bottom of the fractionating tower 16a is forced by way of the pipe line 17 and the hot oil pump 18 through a preheater or economizer 19, where the liquid oil is vaporized and passes by way of a line 20 into an evaporator 21. The stock which is not vaporized at the temperatures prevailing in the evaporator, which may be, for example, 650° F., accumulates as a liquid in the bottom of the evaporator and is permanently removed from the system by way of the line 22 as fuel oil. The vapors pass overhead from the evaporator and enter the converter by way of the pipe line 23. In the converter the temperature of the vapors is rapidly raised to conversion temperatures preferably in excess of 1000° F. and are delivered to the heat exchanger as previously described wherein the operation above given is repeated. The preheater 19 may receive its sources of heat from the outlet gases of the converter. An excess oil container 24 may be connected with the bottom of the fractionating tower 16a for the purpose of regulating the quantity of material introduced into the system. From the fractionating tower 16a the vapors are suitably discharged and condensed and may be purified by any suitable method, such as treatment with fuller's earth or the ordinary acid and alkali method, the final condensate being suitable for use as a motor fuel and possesses a high anti-knock value.

The provision of the closed coil 4 in the heat exchanger 3 provides for the separate withdrawal from the system of the so-called "straight-run" gasoline fractions of the charging stock and the cracked distillate produced by the operation of the conversion zone. This is of considerable importance in that the straight-run gasoline and cracked distillate possess markedly different characteristics, especially in the matter of relative anti-knock values. The cracked distillate is usually greatly superior to the straight-run product in this respect and therefore the present invention provides for the separate withdrawal from the system of the straight-run and cracked distillates.

What is claimed is:

1. The method of treating petroleum which comprises subjecting petroleum from which free gasoline has been removed to heat in a still to vaporize the petroleum, conducting the vapor to a cracking apparatus and there subjecting the vapor to a temperature sufficient

to break down the high boiling point compounds into compounds having relatively low boiling points, conducting the highly heated cracked vapors from the cracking apparatus to a separate receptacle, in passing a 5 charging stock containing free gasoline through a closed coil arranged within said receptacle, whereby such charging stock is heated sufficiently to effect the vaporization of the low boiling point compounds thereof, 10 in separately removing said vaporized low boiling point compounds from the charging stock, and in separately discharging the higher boiling point compounds of the charging stock into the receptacle in liquid form 15 for admixture with the vapors discharged from said cracking apparatus, to lower the temperature of said cracked vapors and to abruptly arrest further cracking reactions 20 therein.

2. In the manufacture of low boiling petroleum oils from high boiling petroleum oils, the process which consists in subjecting topped petroleum oils from which free gasoline has been removed to temperatures in excess of 1000° F. to vaporize such oils and convert the high boiling point fractions thereof 25 into fractions having relatively low boiling points, in discharging the cracked vaporized fractions at the temperature specified into a separate receptacle, in passing a charging stock containing free gasoline to a heat exchanger arranged in said receptacle to heat such charging stock by indirect heat exchange with said vapors so that the temperature 30 of the charging stock will be elevated sufficiently to vaporize and liberate the free gasoline contained therein from the remaining liquid oils of higher boiling range, in 35 separately removing the vaporized free gasoline from said higher boiling oils, and in then returning the latter to said receptacle for direct and intimate contact with the cracked vapors introduced into the receptacle. 40

3. A method of treating petroleum which 45 comprises subjecting the vapor of a petroleum from which free gasoline has been removed to temperatures sufficient to break down the high boiling point compounds into 50 compounds having relatively low boiling points, in passing such cracked vapors into a separate receptacle, in passing a liquid charging stock through said receptacle in indirect heat exchange with the cracked heated vapors within the receptacle, whereby said 55 charging stock is heated sufficiently to vaporize and liberate the free gasoline contained therein, separately removing the free gasoline from the charging stock, and in returning the remaining body of the charging stock 60 to the interior of said receptacle so that said body will be brought into direct contact with the cracked vapors entering said receptacle. 65

4. A method of treating petroleum which 70 comprises, first, subjecting petroleum from 75 which free gasoline has been removed to heat in a still to vaporize the petroleum; second, conducting the vapor to a cracking apparatus and there subjecting the vapor to a temperature in excess of 1000° F. to break down the high boiling point compounds into compounds having relatively low boiling points; third, conducting the highly heated cracked vapor from the cracking apparatus to a separate receptacle wherein said vapors are 80 cooled to a noncracking temperature below substantially 600° F.; fourth, in passing a charging stock containing free gasoline through a coil contained in said receptacle for the purpose of heating said charging stock sufficiently to vaporize the unvaporized free gasoline contained therein by indirect heat exchange with said cracked vapors; fifth, separately removing the free gasoline from the charging stock and separately collecting the same; and, sixth, returning the remaining body of the charging stock to said receptacle for direct and intimate admixture with the cracked vapors discharged into said receptacle so that the relatively cooler charging 85 stock will effect an abrupt reduction in the temperature of the cracked vapors. 90

5. A method of treating petroleum which 95 comprises, first, subjecting petroleum from which free gasoline has been removed to heat in a still to vaporize the petroleum; second, conducting the vapor to a cracking apparatus and there subjecting the vapor to a temperature in excess of 1000° F. to break down the high boiling point compounds into compounds having relatively low boiling points; third, conducting the highly heated cracked vapor from the cracking apparatus to a separate receptacle wherein said vapors are 100 cooled to a noncracking temperature below substantially 600° F.; fourth, in circulating a charging stock containing free gasoline through a coil contained in said receptacle for the purpose of heating said charging stock sufficiently to vaporize the free gasoline contained therein by indirect heat exchange with said cracked vapors; fifth, separately removing the thus vaporized free gasoline from the charging stock and collecting the same; sixth, returning the remaining liquid body of the charging stock to said receptacle for direct and intimate admixture with the cracked vapors discharged into said receptacle so that the relatively cooler charging stock will effect an abrupt reduction in the temperature of the cracked vapors; seventh, separately removing the vapors from the receptacle; and, eighth, removing the unvaporized oil from said receptacle and passing the same 105 through the cracking zone of the system. 110

In testimony whereof I affix my signature.
